UNITED STATES PATENT OFFICE.

FRELING C. FOSTER, OF CHICAGO, ILLINOIS, ASSIGNOR TO THE UNION
TYPE FOUNDRY, OF SAME PLACE.

DESIGN FOR A FONT OF PRINTING-TYPE.

SPECIFICATION forming part of Design No. 18,626, dated September 25, 1888.

Application filed August 3, 1888. Serial No. 281,889. Term of patent 3½ years.

To all whom it may concern:

Be it known that I, FRELING C. FOSTER, a citizen of the United States, residing at Chicago, county of Cook, State of Illinois, have invented and produced a new and original Design for a Font of Printing-Type, of which the following is a specification, reference being had to the accompanying typographic print.

My design consists of a font of printing-type composed of capital letters in what is known as the "Gothic" style, of equal heights, with even unshaded lines spread or flattened at the ends, with wavy horizontal lines and cross-lines at unequal heights, and figures, dollar-mark, and punctuation-marks of the same style.

The A is formed with flattened or truncated apex. B, D, E, F, L, P, Z, and 7 have wavy horizontal lines. U, V, W, and Y have one leg shorter than the other. G is formed on an eccentric curve with vertical stroke, terminated by a horizontal stroke with drooping terminal. S is formed with convolutions of unequal size; and other minor peculiarities, as shown in the print.

What I claim, and desire to secure by Letters Patent, is—

The design for a font of type, consisting of capital letters of Gothic style, of equal heights, with even unshaded lines spread or flattened at the ends, with wavy horizontal lines and cross-lines at unequal heights, substantially as shown and described.

FRELING C. FOSTER.
